LOCKING DEVICE FOR FLUORESCENT BULBS

Fred Binder and Burton A. Binder, both of
2555 Bellevue, Detroit 7, Mich.

Filed Feb. 11, 1959, Ser. No. 792,485

5 Claims. (Cl. 339—54)

This invention relates to a locking device for fluorescent bulbs and more particularly to a device for locking the end of an elongated type fluorescent bulb to its support post, to which it is connected, to prevent the bulb from falling off the post or from having its electrical connection broken.

Elongated type fluorescent bulbs are normally supported at their opposite ends upon support posts connected to a lighting fixture. The ends of the bulbs plug into the post and are usually electrically connected thereto. The connections between the bulb and the posts normally are adequate to prevent the bulb from falling off the post. However, under certain conditions, such as within a factory where machinery causes vibration or where there are shocks or loads imposed upon the bulb, or where the posts are slightly defective in gripping the ends of the bulb, bulbs occasionally fall free from their posts. In such cases, the bulb falls down and breaks. Depending upon the type of fixture, the bulb may fall to the floor and shatter or it may fall to the bottom of the fixture and remain there.

Thus, it is an object of this invention to provide a locking device which locks the ends of the fluorescent bulb to its two support posts so that the bulb cannot be removed from the support posts regardless of loads or vibration or the like until some individual manually unlocks the locking device to remove the bulb.

A further object of this invention is to form such a locking device inexpensively and preferably out of a single sheet of thin springy material, such as a thin gage sheet metal, formed to lock against the support posts without any separate mechanical fastening means.

Another object of this invention is to provide such a locking means which frictionally locks itself to the support posts without any separate mechanical fastening means, and which grips the bulb between a pair of jaws to prevent the bulb from falling off the posts.

These and other objects and advantages of this invention will become apparent upon reading the following description of which the attached drawings form a part.

With reference to the attached drawings:

Fig. 1 is a perspective view of a conventional support post, the locking device, and a bulb end, to indicate how they would be assembled together.

Fig. 2 is a front elevation of the locking device per se, and

Fig. 3 is a side view taken in the direction of arrows 3 on Fig. 2; and

Fig. 4 is a top view taken in the direction of arrow 4 of Fig. 2.

With reference to the drawings, Fig. 1 shows a conventional fluorescent electric fixture support post 10 having a front face 11 provided with a bulb receiving socket 12 into which the end 13 of an ordinary elongated fluorescent bulb 14 is connected.

The post is provided with a base 15 which is secured to the lighting fixture and to which the electrical connections are made. The post and the bulb are conventional

2

and are of the type normally found in overhead fluorescent lighting fixtures.

The improvement hereof comprises the locking device 20 which is formed to lock the bulb end to the support 5 post.

The locking device is preferably formed of a single sheet of thin, springy sheet material, such as springy sheet metal, and is bent into the form of a back portion 21 adapted to fit against the back of the post with the side 10 edges of the back portion being bent into side flanges 22 to form a channel 23. The post 10 fits snugly within the channel.

A portion of the side flanges near one end of the locking device is bent along the free edges thereof into front 15 flanges 24 which terminate in spring portions 25 which are bent towards the back portion 21. The front flange portion 25, being springy, resiliently moves away from the back portion 21 when the post is slipped into the channel 23 and spring grips the post to prevent removal 20 of the locking device from the post except under the application of a heavy pull or force.

Near the opposite end of the device, the side flanges 23 are extended into springy arms 28 which terminate in 25 jaws 29. The jaws are preferably covered by rubber or the like, resilient sleeve 30, so that they may not scratch or mar the bulb which is grasped between the jaws 29. Note, in Figs. 2, 3 and 4 the sleeve is omitted for illustration purposes.

The jaws are resiliently compressed towards each other 30 and are locked in compressed position to thus grasp and grip the end 13 of the fluorescent tube 14. It can be seen, that the jaws are arranged to be in alinement with the socket 12 of the post 10 and are on opposite sides of the post.

35 The means for compressing and locking the jaws comprises a latch 35 in the form of a wire bent into a U-shape with the ends 36 of the legs of the wire being bent to pivotally fit around lugs 37 struck out of the side flanges of the locking device. The bight of the wire 40 passes around the outside of arms 28 and over the top of the arms as shown in Fig. 1 and is so dimensioned that when the U-shape is pivoted away from the back portion 21, the arms are compressed towards each other. The arms normally diverge from each other and are pressed 45 together into the dotted position shown in Fig. 4 by means of the U-shaped latch.

The latch is held in locking position by means of stops or bumps 39 formed in the arms. When it is desired to 50 unlock the device, the latch is pivoted toward the back portion around pivot lugs 37 and the resiliency of the arms permit the latch to pass over the bumps 39 whereupon the arms open relative to each other and permit removal of the bulb from the jaws.

55 With this device, the bulb is securely locked to the posts so that it cannot be removed except deliberately and with great manual effort. Moreover, the locking device is not permanently secured to the post and may be easily secured to the post by slipping it over the post. Hence, the locking device may be easily mounted upon any post 60 where there is a danger of a bulb becoming disengaged.

This invention may be further developed within the scope of the following attached claims. Accordingly, it is desired that the foregoing description be read as being merely illustrative of an operative embodiment of 65 this invention and not in a strictly limiting sense.

We claim:

1. A locking device for locking the end of a fluorescent bulb to a holder of the type having a post with a front face upon which the bulb end is supported and to which it is connected, comprising a single flat sheet of thin springy material, such as sheet metal, bent into a back portion of a shape to fit against the back of the bulb support post,

the side edges of the back portion each being bent to form side flanges to form a channel with the back portion for enclosing the post in said channel and each of the side flanges having a front flange bent towards the opposite side flange and spaced from the back portion to extend around the front face of the post to thus envelop the post between the back portion, the side flanges and the front flanges, and the side flanges also having a pair of springy arms integral therewith and extending outwardly therefrom a sufficient distance to extend beyond the front face of the holder and each of the arms terminating in a jaw with the jaws being oppositely facing and arranged in front of the front face for gripping the sides of a fluorescent bulb connected to the post front face, and means for compressing the arms towards each other and holding the arms in compressed position so that the jaws may grip a bulb between them, and means releasably securing the holder within said channel.

2. A construction as defined in claim 1, and said means for releasably securing the holder within the channel consisting of at least a portion of said front flanges being bent towards the back portion to contact and resiliently press against the front face of the post so as to press the post against the back portion and thereby frictionally and releasably secure the post between the back portion and the front flanges.

3. A construction as defined in claim 1 and wherein the compressing means comprises a latch in the form of a wire bent into a U-shape, with each of the ends of the legs of the U being pivotally connected to a respective side flange and with the bight of the U passing around the outside of the arms, with the arms being enclosed within the two legs of the U-shape, the free ends of the arms normally diverging away from each other and the space between the legs of the U-shape being less than the space between the normally diverging arms near their respective jaws, so that pivoting of the wire towards the jaws compresses the arms towards each other into a bulb locking position, and stop means formed on the

arms for releasably locking the wire in the pivoted position where it compresses the arms towards each other.

4. A locking device for locking the end of an elongated type fluorescent bulb on a holder of the type having an elongated post with a front face upon which an end of the bulb is connected, comprising a single, flat sheet of thin, springy metal formed into an elongated back portion arranged to fit against the back of the post and having its long side edges bent into side flanges to form a channel having an open mouth into which channel a post may be snugly fitted; the free edge of each side flange, near one end of the device, being bent into a springy front flange extending toward the opposite side flange, which front flanges are spaced in front of the back portion to at least partially close a portion of the open mouth of the channel and which front flanges are arranged to overlap and press against a part of the front face of the post to squeeze the posts towards the back portion and thus secure the posts within the channel; the free edges of each of the side flanges being extended, near the opposite end of the device, into normally diverging springy arms terminating in jaws arranged on opposite sides of the post, and means for compressing the arms towards each other and locking the arms in compressed position for gripping a bulb between the jaws.

5. A construction as defined in claim 4 and including at least a portion of the front flanges being bent towards the back portion and being resiliently movable towards and away from the back portion for spring pressing the post against the back portion within the channel.
